CHARLES FURBER, OF LONDON, ENGLAND.

Letters Patent No. 84,943, dated December 15, 1868.

IMPROVED DRESSING-GLASS REFLECTOR.

The Schedule referred to in these Letters Patent and making part of the same.

To all whom it may concern:

Be it known that I, CHARLES FURBER, of London, in the Kingdom of England, have invented a new and improved Dressing-Glass Reflector; and I do hereby declare that the following is a full, clear, and exact description thereof, which will enable those skilled in the art to make and use the same, reference being had to the accompanying drawings, forming part of this specification.

This invention relates to improvements in dressing-glass reflectors, whereby it is designed to provide an arrangement of the same that will facilitate the inspection of the back part of the head, or other portion of the body, while dressing.

The accompanying drawing represents a perspective view of my invention.

A represents a metallic bracket, suitably arranged to be secured, by screwing or otherwise, to the frame of a dressing-glass, preferably at the back of the top of the same, which is provided with a short tube, B, into which a set-screw, C, projects.

D represents a tubular support for the reflector E, which may be inserted in the tube B, at one end, and secured there by the set-screw C, and which is provided, in its other end, with a bent rod, F, closely fitting the bore of the tube, and which may be adjusted in or out of the tube, thereby extending or shortening the sup-

port, as desired, for suspending the reflector E at the required distance from the glass.

The reflector is connected to the curved end of the rod by a joint, which will admit it to be adjusted, and hold it at any angle fronting the glass.

By this simple and convenient arrangement, a dressing-glass reflector may be readily attached to any glass, and may also be taken off with the same facility, and the reflector and its supporting-rods may be disconnected from the bracket A, and stored away, when not required for use.

The construction of the bracket may be varied to some extent, and the manner of joining the reflector to the rod may be any which is found best.

I claim as new, and desire to secure by Letters Patent—

The bent rod F, jointed to the centre of the back of the reflector E, whereby the latter is adjustable to any desired angle, with reference to said rod, which is adapted to slide within the tube D, adjustably connected to the short tube B, upon the glass-frame, as herein shown and described.

The above specification of my invention signed by me, this 3d day of October, 1868.
